UNITED STATES PATENT OFFICE.

WILLIAM BEE SCHUYLER, OF ST. LOUIS, MISSOURI.

SACK-CLEANER.

SPECIFICATION forming part of Letters Patent No. 724,055, dated March 31, 1903.

Application filed October 16, 1902. Serial No. 127,549. (No model.)

To all whom it may concern:

Be it known that I, WILLIAM BEE SCHUYLER, a citizen of the United States, residing at St. Louis, in the State of Missouri, have invented certain new and useful Improvements in Sack-Cleaners; and I do declare the following to be a full, clear, and exact description of the invention, such as will enable others skilled in the art to which it appertains to make and use the same.

This invention relates to a machine for cleaning bags or sacks, particularly those which have contained flour; but it may be used to clean any kind of bag or sack.

15 The object of the invention is to provide a machine which is simple of construction, highly efficient in use, and inexpensive of production and one in which the cleaning action is performed by agitating the sacks without 20 beating, thereby preventing injury to the sacks during the process of cleansing.

With this and other minor objects in view the invention consists of certain novel features of construction, combination, and arrangement of parts, as will be hereinafter 25 more fully described, and particularly pointed out in the appended claims.

In the accompanying drawings, Figure 1 is a vertical longitudinal section of a bag or sack 30 cleaning machine embodying my invention. Fig. 2 is a vertical cross-section of the same. Fig. 3 is a sectional plan view.

Referring now more particularly to the drawings, 1 represents the inclosing casing of 35 the machine, which is preferably of oblong rectangular form, but may be of any suitable form and size. This casing is provided with doors 2 for the insertion and removal of the sacks, said doors forming the side and end 40 walls of the machine and consisting, preferably, of wooden frames hinged at 2' to the casing and covered with thin foraminous material 3, such as cheese-cloth, so as to allow air to freely circulate through the machine, 45 but to prevent the escape therefrom of the flour or dirt from the sacks confined therein. Any desired number and arrangement of doors may be employed, and where the doors are not so arranged as to completely form the 50 side and end walls the spaces unoccupied by the doors may be covered by foraminous ma-

terial in a similar manner, giving ventilation through the machine from side to side and end to end, as will be readily understood.

Extending longitudinally of the casing at 55 the base and on the interior thereof are bars or beams 4, from which project headed vertical standards or arms 5, serving as supports for the sacks. These bars are fixed to the end transverse beams of the machine, and the 60 arms are fixed to the bars and are therefore relatively stationary. Arranged parallel with the bars 4 are other bars 6, which are connected at their ends by transverse bars 7, forming a rectangular frame which is adapted 65 to reciprocate longitudinally of the casing on friction-rollers 8, mounted upon the base of the machine. These bars 6 are disposed between and on opposite sides of the bars 4, and carry vertical arms 9, which reciprocate 70 with said bars 6 and are therefore movable relatively to the arms 5. One end of the reciprocating frame is connected by a pitman-rod 10 with a crank 11 on a shaft 12, which shaft is supported by suitable brackets or 75 standards 13 and carries tight and loose pulleys 14 and 15, whereby the shaft may be driven and when driven will impart reciprocating motion to said frame.

As shown clearly in Figs. 2 and 3, the arms 80 5 on each bar 4 are equal in number to the arms 9 in the bars 6 of the reciprocating frame, and normally said arms 5 and 9 are disposed alternately in transverse rows, which rows are constituted in the present instance by two 85 stationary arms 5 and three reciprocating arms 9. These rows are of a length to receive a certain size or certain sizes of sacks, a row of five arms spaced a determined distance apart being adapted for the reception of a 90 seventeen-inch sack when all the arms are used or of a twelve-inch sack when four arms (two stationary and two reciprocating) are used. Hence I may easily adapt the machine to clean a number of different sizes of sacks 95 by the simple process of increasing the number of arms in a row, whereby different sizes of sacks may be cleaned at one time by one and the same machine.

Heretofore it has been proposed to place 100 sacks to be cleaned on a certain size of frame and to clean the sacks by the action of beat-

ers. This is objectionable for two reasons—
first, because the use of a certain size of
frame permits of the cleaning only of sacks
of one size in the machine, so that if the op-
erator should have several lots of different-
sized sacks to clean he would be required to
use several machines, one for each size of
sack, and, second, because the action of beat-
ing the sacks to remove the dirt and dust
therefrom weakens the sacks by the beating
out of lint and threads and the straining of
the material. My invention is designed to
obviate these objections in a simple and ef-
fective manner. It has been before stated
that the rows of arms may permit of the ap-
plication of different-sized sacks, which over-
comes the first objection, and I overcome the
second by cleaning the sacks by agitation
(without blows) and wind-pressure, whereby
the dust and dirt are removed without caus-
ing any strain upon the material of which the
sack is made.

The operation of cleaning the sacks is ac-
complished as follows: The doors of the cas-
ing are opened and the sacks placed one upon
each transverse row of arms, the higher sta-
tionary arms 5, which project up into the
sacks, serving to support the sacks, while the
movable arms 9, which also project up into
the sacks, but to a less distance, set up the
agitation. After the sacks have been applied
and the doors closed the reciprocating frame
is set in motion, and the arms 9 are thereby
caused to vibrate or agitate the sacks without
beating, causing the sacks to shake or flutter
at a rapid rate, whereby the dirt is loosened
up and dislodged from the sacks. This shak-
ing action or motion of the sacks, which is
equivalent to the hand motion of shaking the
dust out of a rug, but much more effective,
produces within the casing a back-and-forth
circulation of the air, which blows the loosened
particles from the sacks and materially as-
sists in dislodging the dust and dirt. It will
thus be seen that the sacks are effectively
cleaned without beating and without strain-
ing or otherwise injuring them.

If desired, the reciprocating frame may
have a bottom 16, of foraminous material,
serving as a sieve to retain the coarser par-
ticles of the materials shaken from the bags or
sacks and allow the fine particles to pass
down into a removable drawer 17, thereby
obviating subsequent sifting.

The arms 9 may be elastic or inelastic, so as
to independently vibrate or remain relatively
stationary as the reciprocating frame recip-
rocates. A vibratory action of these arms
will assist in cleaning the sacks without beat-

ing, but by merely more vigorously shaking 60
the sacks.

From the foregoing description, taken in
connection with the accompanying drawings,
the construction and operation of the inven-
tion will be readily understood without re- 65
quiring a more extended explanation.

Various changes in the form, proportion,
and the minor details of construction may be
resorted to without departing from the prin-
ciple or sacrificing any of the advantages of 70
this invention.

Having thus described my invention, what
I claim as new, and desire to secure by Letters
Patent, is—

1. In a sack-cleaner, a row of arms to re-
ceive the sack, some of said arms being sta-
tionary to support the sack and the others
movable to shake the sack, and means for
imparting direct motion to said movable
arms, substantially as described. 75

2. In a sack-cleaner, a row of arms to re-
ceive the sack, some of said arms being sta-
tionary to support the sack and the others
movable to shake the sack, and means for re-
ciprocating said movable arms, substantially 85
as set forth.

3. In a sack-cleaner, two series of arms, one
being stationary and the other movable, the
stationary series being adapted to support the
sacks and the movable series to agitate the 90
sacks, substantially as described.

4. In a sack-cleaner, the combination of an
inclosing frame, a sack-holding frame therein
provided with supports for the sacks, a recip-
rocating agitator adapted to impart a swing- 95
ing or fluttering motion to the sacks to agi-
tate them and remove the dirt and dust
therefrom, said agitator carrying a sieve to
separate the coarser from the finer particles
of dirt, a receptacle into which the finer par-
ticles of dirt are adapted to drop, and means
for reciprocating said agitator, substantially
as described.

5. In a sack-cleaner, the combination with
a casing, of stationary arms for supporting 105
the sacks, reciprocating arms arranged alter-
nately with the stationary arms to produce
transverse rows, and means for reciprocat-
ing the reciprocating arms, substantially as
shown and described.

In testimony whereof I have hereunto set
my hand in presence of two subscribing wit-
nesses.

WILLIAM BEE SCHUYLER.
